ANDREW A. KRAMER, OF KANSAS CITY, KANSAS.

METHOD OF MANUFACTURING FENCE-POSTS.

1,111,909.

Specification of Letters Patent. Patented Sept. 29, 1914.

Application filed May 10, 1912. Serial No. 696,475.

To all whom it may concern:

Be it known that I, ANDREW A. KRAMER, a citizen of the United States, residing at Kansas City, in the county of Wyandotte 5 and State of Kansas, have invented certain new and useful Improvements in Methods of Manufacturing Fence-Posts; and I do declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

My invention relates to a method of manufacturing concrete fence posts, and has for its object to provide a method of manufacture whereby posts may be molded quickly 20 and cheaply, and adapted, during the molding process, for receiving wire fasteners. In accomplishing these, and other objects, which will be disclosed in the following description, I have provided the improved 25 tails of structure hereinafter described and illustrated in the accompanying drawings, wherein:

Figure I is a view of a post, constructed according to my invention, showing fence 30 wires in place, and showing part of the casting broken away to disclose the concrete contained therein. Fig. II is an enlarged vertical section of parts of the post, showing the reinforcing wires, and fastener opening, 35 and showing one of the fasteners in place and holding a fence wire. Fig. III is a vertical section of the mold in pouring position, with reinforcing wires in place. Fig. IV is a longitudinal section of a portion of 40 the mold, showing the means for forming an aperture for receiving a wire fastening member. Fig. V is a detail view of a preferred form of fastening member. Fig. VI is a view of a number of nested molds.

45 Referring more in detail to the parts:— 1 designates a mold or form which may be composed of sheet metal, stiff paper, or other material which will hold its shape while concrete is poured thereinto and while the 50 concrete is becoming set or hardened. The form is tapered at one end and provided with apertures 2, arranged in pairs, at opposite sides of the form, so that a spike or rod 3 may be projected through the 55 apertures and extended across the interior of the

form, so that concrete may be poured there-around. There may be as many pairs of the apertures 2 as may be necessary to carry a desired number of fence wires and the apertures may be spaced longitudinally on the 60 post to correspond with the spacing desired for the fence wires.

4 designates reinforcing rods, or wires, which extend longitudinally through the center of the form, or mold, and are woven 65 over the spikes 3 so that they follow a tortuous path throughout the length of the post and are held in the center of the form.

In order to prevent the reinforcing members from moving laterally along the spikes 70 prior to the pouring of the concrete, I make the form apertures 2 of sufficient diameter to receive the tubular members 5 which are adapted to surround the spikes 3, so that when the latter have been positioned the 75 tubes may be moved into the form from opposite sides thereof so that their inner ends will abut against the reinforcing members and move the latter to the center of the form.

In actual practice, I provide a frame, (not 80 shown) within which a number of forms 1 may be mounted, with their smaller ends pointed downwardly. With the forms in this position and with means provided for stopping the lower ends of the forms, the reinforcing wires 4 are placed within the forms 85 and the spikes 3 projected through the apertures 2 so that they extend alternately on opposite sides of the reinforcing members. After the spikes are in place, the tubes 5 are 90 placed on the opposite ends of the spikes and moved through the form apertures to center the reinforcing members. With the parts so arranged, concrete is poured into the large upper ends of the forms so that it 95 surrounds the reinforcing members and spikes and fills the form. The material is then left to harden or set, and at the proper time, or before the material has completely hardened, the tubes 5 and spikes 3 are withdrawn to leave the transverse apertures 6 through which wire fastening members may be extended when the post is finally erected.

When the post is set in the ground the 105 fence wires 7 are strung therealong and fastener members 8, preferably comprising staples having expanded heads 9, which project over the fence strands and through the apertures 6, the staples or fasteners being of such length that their free ends will project 110

through the post and may be bent back to form keepers 10.

It is apparent that the forms, or molds, may be made up at the factory and shipped 5 to the place where they are to be used, the tapered construction enabling them to be nested as illustrated in Fig. VI, so that they may be compactly arranged for shipping or storing. The forms may then be set up 10 near the place they are to be used and filled with concrete, as many forms as are to be used being filled at the same time if necessary, as the user does not need to empty the form 15 after one post has been made in order to use it for another post.

By having the shell or form used as part of the post, the material does not need to be left to become hardened as long as if the post were required to carry itself, as the 20 form will hold the material, whereas if the form were removed the material might not have sufficient strength to retain its shape.

It is apparent that any material having sufficient body to hold its shape while the 25 concrete is being poured and set will answer for the form, as even should the shell crumble or rust within a short time after it is set in the ground the post would not be materially affected, as the wasting of the shell 30 would merely expose the solid reinforced post.

Having thus described my invention, what

I claim as new therein and desire to secure by Letters-Patent is:—

1. The method of manufacturing fence 35 posts consisting in providing a form, having openings therein, arranging reinforcing members longitudinally within the form, projecting spikes through openings in the form and alternately on opposite sides of 40 the reinforcing members, filling the form with concrete to embed the reinforcing members, withdrawing the spikes before the concrete has set, and allowing the concrete to set, whereby the form is made an integral 45 part of the post.

2. The method of manufacturing fence posts consisting in providing a form having openings therein, arranging reinforcing within the form, projecting spikes through 50 the form openings, projecting tubular members over the spikes and against the reinforcing to center the latter, filling the form with concrete, removing the tubular members and spikes before the concrete has set, 55 and allowing the concrete to set whereby the form is made an integral part of the post.

In testimony whereof I affix my signature in presence of two witnesses.

ANDREW A. KRAMER.
